The ornamental design for a smart sensor, as shown and described.

DESCRIPTION

FIG. 1 is a perspective view of the smart sensor looking downwardly from the front end thereof.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a front view of the smart sensor; and,

FIG. 9 is a perspective view of the smart sensor.

In the drawings, the broken lines depict environmental subject matter only and form no part of the claimed design.
